(57) **CLAIM**

The ornamental design for a detergent inlet for washing machine, as shown and described.

DESCRIPTION

1.0 Detergent inlet for washing machine.

1.1 —Top left elevational view;

1.2 —Front elevational view;

1.3 —Rear elevational view;

1.4 —Left side elevational view;

1.5 —Right side elevational view;

1.6 —Top plan view;

1.7 —Bottom plan view;

1.8 —Cross sectional detail view;

1.9 —Top left elevational view of the article in a closed condition; and

1.10 —Top left elevational view shown in use on a washing machine.

The broken line showing of a washing machine and detergent dispenser depicts environment and forms no part of the claim.

1 Claim, 10 Drawing Sheets
